UNITED STATES PATENT OFFICE.

ISAAC GOODMAN, OF PHILADELPHIA, PENNSYLVANIA, ASSIGNOR TO HIMSELF, ABRAHAM KAUFMAN, BERNHARD STROUSE, WILLIAM KAUFMAN, AND SYLVESTER C. KLOPFER, ALL OF SAME PLACE.

DESIGN FOR TRIMMING.

SPECIFICATION forming part of Design No. 18,033, dated January 31, 1888.

Application filed December 17, 1887. Serial No. 258,235. Term of patent 3½ years.

To all whom it may concern:

Be it known that I, ISAAC GOODMAN, a citizen of the United States, and a resident of Philadelphia, Pennsylvania, have invented a new and original Design for Trimming, of which the following is a specification.

My design is fully shown in the accompanying drawing. The design comprises a strip or band forming a succession of loops, the loops being disposed in opposite outer series, A, and an intermediate series, B, the loops of the outer series forming leaf-like figures, as shown. The strip or band comprises the large portion *a* with prominent transverse ribs, and the small portion *b* plain or without prominent ribs, this small portion lying at the side of and forming a border for the large ribbed portion of the strip or band.

I claim—

The within-described design for a trimming, 20 said design consisting of the intermediate series of loops, B, the outer series of loops, A A, forming leaf-like figures, said loops comprising a large ribbed portion, *a*, and a finer portion, *b*, lying at the side of the large portion, all substantially as shown and described. 25

In testimony whereof I have signed my name to this specification in the presence of two subscribing witnesses.

ISAAC GOODMAN.
